United States Patent Office

Des. 229,834
Patented Jan. 8, 1974

229,834

TWO-WAY RADIO HOUSING OR SIMILAR ARTICLE

Terrence N. Taylor, Cary, Ill., assignor to
Motorola, Inc., Franklin Park, Ill.

Filed Dec. 15, 1971, Ser. No. 208,528

Term of patent 14 years

Int. Cl. D14—03

U.S. Cl. D26—14 K

FIG. 1 is a perspective view of a two-way radio housing or similar article showing the front, top and one side of my new design;

FIG. 2 is a view of the housing side not shown in FIG. 1.

FIG. 3 is a view of the bottom of the two-way radio housing; and

FIG. 4 is a view of the rear side of the two-way radio housing shown in FIG. 1.

The broken lines are shown for illustrative purposes only.

I claim:

The ornamental design for a two-way radio housing or similar article, substantially as shown and described.
